United States Patent Office

Des. 204,519

Patented Apr. 19, 1966

204,519

PRINTING MACHINE FOR CREDIT CARDS OR THE LIKE

William Plumb Barbour, Fairfax County, Va., assignor to Farrington Business Machines Corporation, Springfield, Va., a corporation of Massachusetts

Filed Oct. 16, 1964, Ser. No. 82,201

Term of patent 14 years

(Cl. D64—11)

Fig. 1

Fig 2

FIGURE 1 is a front perspective view of a printing machine for credit cards or the like showing my new design.

FIGURE 2 is a back perspective view thereof.

I claim:

The ornamental design for a printing machine for credit cards or the like, as shown.

References Cited by the Examiner

UNITED STATES PATENTS

D. 157,913 3/1950 Senechal ----- D64—11

D. 186,832	12/1959	Rutkus -----	D64—11
D. 193,743	10/1962	Maul et al. -----	D64—11
D. 194,463	1/1963	Jagger et al. -----	D26—5
D. 195,624	7/1963	Behr et al. -----	D26—5
D. 197,997	4/1964	Van Acker -----	D64—11

EDWIN H. HUNTER, Primary Examiner.

LOUIS J. PERLSTEIN, Examiner.